UNITED STATES PATENT OFFICE

EUGENE ROBERTS, OF SALT LAKE CITY, UTAH, ASSIGNOR TO THE WESTERN STATES MACHINE COMPANY, OF SALT LAKE CITY, UTAH, A CORPORATION OF UTAH

MEANS FOR AUTOMATICALLY CONTROLLING CENTRIFUGAL MACHINES

Application filed December 8, 1925. Serial No. 74,111.

This invention relates to the centrifugal purification of sugar and comprises a system of automatic control applied to a centrifugal machine by which the successive cycle of operations performed are accurately and scientifically regulated to suit the particular requirements of different grades of sugar that are received for treatment, and thus avoid the loss and waste incident to the irregular and unreliable control heretofore maintained by the machine operator.

Centrifugal purification of sugar or like solids involves a cycle of operations as follows: first, the purging or centrifugal elimination of free syrup from the sugar grains; second, centrifugal washing to remove the coating of syrup that adheres to the sugar grains by means of a fine spray directed against the revolving sugar mass walled up 20 on the inside of the basket; third, the partial drying of the wet sugar to the proper stage to adapt it for the next operation of granulating. After the requisite degree of dryness is attained, the centrifugal is slowed down, or stopped, to permit discharging the purified crystals upon an underneath conveyor, which carries it to the granulator.

Two operations may be advantageously performed by an attendant, namely, the loading 30 of the sugar to the basket and, secondly, where a valved flat bottom basket is used, instead of a conical self-discharging basket, the discharging of the sugar through the bottom when the machine has slowed down sufficiently to permit the use of discharger plow.

If the purging operation is continued too long before spraying the adherent coating of syrup becomes hard, while if the spray be turned on before the free syrup is extracted, 40 the residue of the free syrup impairs the efficiency of the washing operation. In either case an excessive amount of water would be required, but tests have shown that every pound of water sprayed upon the sugar wall 45 dissolves about three pounds of sugar so that any excess of water applied involves much waste of valuable material. It is also true that if the drying operation, following the washing, be continued too long the sugar becomes so hard that it may smash the dis-

charger and cause a disastrous accident. If, on the other hand, the sugar, when discharged, be not dry enough the excess moisture will adversely affect the granulating process. Different batches or grades of 55 sugar require appropriate variations in the duration of the different steps of the cycle.

With the use of the automatic controlling apparatus, forming the present invention, the duration of every step in the cycle of operations may be exactly predetermined by a skilled overseer making the proper adjustments and may be varied to meet requirements for different grades of sugar. The attendant, being merely required to load and 60 start the machine with no need of attention until the machine is automatically slowed down or stopped for discharging, can readily care for six or eight machines instead of only two machines as heretofore, and produce a 70 more uniform and better quality of product.

In general the invention consists in combining with the centrifugal machine and its accompanying brake, and brake device, an automatic control mechanism set in operation when the operator starts the machine, and acting to determine precisely the duration of the whole cycle of operations, including both the purging and the washing of the sugar.

In the accompanying drawings is illustrated a concrete embodiment of the principles of this invention, in which:

Figure 1 is a front elevation showing the mechanism as applied to the driving, the braking and the washing mechanism of a centrifugal.

Figure 2 is a detail view showing, in plan, a shipper-shaft by which the machine is started in operation and is stopped at the end 90 of its appropriate cycle.

Figure 3 is a detail showing, in front elevation, the torque-spring adjusting means by which the shipper-shaft is returned to idle position.

Figure 4 is a front elevation of the timer mechanism by which the automatic sprayer is set in operation and by which the machine is stopped after the spraying operation is finished.

Figure 10 is a front elevation of the brake mechanism.

In order to make clear the general nature 15 of this invention I will first explain what is accomplished by the mechanism hereinafter explained.

The cycle of operations for purging and 20 washing sugar or like material in centrifugal machines will vary somewhat, according to the character of the material being treated. In general, however, in the purging and washing of sugar the basket is spun or rotated at about 1100 R. P. M. for a period of perhaps 25 a little over one minute after the machine has reached its maximum speed from the state of rest. After the material has been sufficiently purged by the centrifugal extraction of the liquid syrup, the operator then turns on the 30 spray with the machine still running in order to wash the grains or crystals and to free them from the adhering syrup. After a pre-determined amount of purging and washing or spraying the machine is stopped and the 35 sugar discharged to allow re-loading the machine. The whole cycle ordinarily consumes three minutes and requires both the attention and the judgment of the workman who regulates these operations.

40 With the use of the present improvements the workman merely throws the starting lever or hand-wheel, thereby operatively connecting the driving mechanism with the centrifugal, and is then free to leave the machine 45 since, after a predetermined period, whose duration is determined according to the adjustment or setting of the mechanism, the sprayer is automatically started and is thereafter automatically stopped, while after the 50 spraying operation the machine itself is stopped by disconnecting the driving mechanism and setting the brake.

The invention is here shown as applied to a 55 belt-driven centrifugal in which the belt runs from a loose pulley on the line shaft or driving shaft 1, to the driving pulley *a* which, according to established practice is secured to the suspension shaft *b*, around its center of suspension or gyration which shaft carries 60 the usual centrifugal basket *c*, which type of machine is illustrated in United States Letters Patent No. 1,627,868, granted to me May 10, 1927.

The loose driving pulley 2 is operatively 65 coupled with the driving shaft 1, by means of

clutch mechanism 3, which is thrown into clutching engagement with the pulley by the lever 4, which is fulcrumed at 4^b, above the line shaft, and has an intermediate connecting pin and roller 4^c, projecting into a grooved cam collar of the clutch mechanism. 70

The starting shaft 9 carries a hand-wheel 8 by which the operator throws it in a clockwise direction to operate the clutch and release the brake and start the centrifugal timing mechanism. This horizontal shaft carries, at its 75 rear end near to the vertical plane of the line-shaft, a pinion 5 which intermeshes with a sector arm 4^a at the lower end of the shipper lever 4 so that the clockwise rotation of the shaft 9 and pinion 5 operates to establish driving connection through the clutch between the line-shaft and the driving pulley 2.

This shipper shaft 9 carries a torsion spring 6 so arranged as to normally rotate the shaft in a counter-clockwise direction, that is, in direction to release the clutch and set the brake. To vary the tension of the torsion spring I secure to the shaft 9 a bracket 9^a, in which is mounted a tangential screw or worm 9^b, which can be rotated by a wrench. This worm meshes with a worm-wheel 6^a which is loose on the shaft and to whose hub is attached one end of the torsion spring 6. The 90 other end of the torsion spring is anchored to a collar 6^b, fast on the shaft. By rotating the worm 9^b in one direction or the other the tension of the torsion spring may be increased or diminished, while the worm acts to maintain the torsion-adjusting worm-wheel 95 against rotation from its adjusted position.

Near its forward end the shipper-shaft 9 carries another pinion 11^b which intermeshes with a sector arm 11^a of a lever 11 whose upper end swings to the left (Figure 1) when the shipper-shaft is set by the operator. The upper end of this lever is provided with a notch or recess to form a shoulder 11^c for the reception of a pin 13^c, carried by the weight arm 13^a, of an angle-arm or lever 13, so that as the weight 13^d causes this weight-arm to drop when the adjacent end of the lever 11 is swung outwardly, the weight-lever and its stop pin 13^c serve to prevent the return of the shaft 9 to its initial position under 110 the torque of the spring 6.

The short arm 13^e of this bell-crank lever 13, is pivotally connected with a trip-rod 15, whose opposite end is connected with a three-arm lever 16 arranged, in this case, on the 115 opposite side of the centrifugal machine.

The trip-lever 11 is fulcrumed at 12, and below its fulcral point is connected with and attached to a connecting-rod or link 50 whose opposite end is attached to a rotatable brake shaft 52, carrying, at its lower end, projecting pins 53 which are connected by means of expanding toggles 54 with the free ends of brake-shoes 55 arranged interiorly of the pulley *a*, 120 125

which is secured to the centrifugal shaft near its end of the belt pulley α . Further details of this brake need not be explained as its construction forms no part of the present invention. It will suffice to state that in Figure 9 the brake shoes are shown expanded against the interior of the brake from which position the brake shoes will be contracted to idle position by rotation of the arm 51 and 5 of the brake-spindle 52 in a counter-clockwise direction. It will therefore be seen that the rotation of the shipper-shaft 9 in a clockwise direction both couples the driving pulley to the drive shaft and, at the same time, 10 releases the brake from engagement with the interior of the centrifugal machine pulley.

The three-arm lever 16, which is operatively connected with the shipper-shaft in 20 the manner described, operates both to start the centrifugal timer, when the brake is released and the clutch is set, and also to trip the weight-arm and allow the torsion spring 6 to set the brake and release the clutch when 25 the cycle of operations is completed.

The timer mechanism is closely associated with the automatic sprayer and is set in operation through the agency of the lever 17, having a link connection 16^a, with the lower 30 end of the lever 16. The lower end of the lever 17 is provided with a clutch-fork 17^a, engaging a groove of a sliding clutch member or coupling member 18, which is itself splined to a horizontal shaft 20 on which is 35 loosely mounted a sleeve 18^c, carrying, at one end, a clutch member 18^a, and at its other end a worm-wheel 18^b, intermeshing with a vertical worm 19, which is constantly rotated while the centrifugal is running through 40 the agency of intermeshing spur gears 19^a, 19^b, and vertical shaft 30, which is driven by means of beveled pinions 30^a and a horizontal shaft 30^b, carried in a suitable housing 30^c, and having its outer end driven by means 45 of a friction pulley 31 pressing against the enlarged portion of the spindle b of the centrifugal. The friction pulley 31 has a worm driving connection with the adjacent end of the horizontal shaft 30^b.

50 The vertical shaft 30, which is driven from the centrifugal spindle, as above explained, performs a two-fold function. It serves to actuate the sprayer mechanism, when the sprayer mechanism is thrown into operative 55 connection therewith, as will be presently explained, and it also serves, when clutch connection is established between the shaft 20 and the worm 19, to drive the centrifugal timer mechanism, whose construction will 60 now be explained.

The actuating element of the time mechanism itself is the longitudinal timer shaft 20 which carries, at one end, a fixed collar 21^a serving as an anchorage for the end of 65 a torsion spring 21 coiled around said shaft

whose opposite end is anchored to a fixed part of the frame.

Near the outer end of said timer-shaft, outside of the housing or bracket 20^a which supports said shaft, is secured a dial plate or disk 22 provided with an inwardly-projecting pin 22^a adapted to abut against a projecting fixed ledge or stop 20^b of the housing or bracket. This dial disk has a circular series of perforations 22^b, into which may be sprung the inner end of a headed plunger or pin 23^a, mounted on a loose arm 23, which is carried by the end of the shaft and which constitutes a knock-off arm by which the shipper is released when the projecting hook end 23^b, of said arm 23 comes in engagement with the inwardly turned hook 41 of the vertical trip rod 40, as will be presently explained.

The parts in Figure 4 are shown with the stop pin 22^a in dotted lines resting against 85 the ledge and, therefore, resisting further reverse rotation of the shaft 20 by its torsion spring 21. It will be seen that this stop pin determines the initial position of the dial plate or disk 22, and also of the knock-off 90 arm 23, which can be set to any circumferential adjustment thereof by means of the latch 23^a. Obviously the nearer the knock-off arm 23 is set to the stop pin 22^a the larger will be 95 the arc of rotation permitted it before it comes into engagement with the hook at the lower end of the trip rod 40, and consequently the longer will be the duration of operation of the centrifugal.

The timer shaft 20 is rotated against the 100 tension of its torsion spring 21 by means of the worm 19 and a worm-gear 18^b the latter being fast on the shaft 20. Such rotation, however, can not take place until the splined clutch element 18 is interlocked with the 105 rotating or driving clutch element 18^a, which occurs through the swinging movement of the timer starting lever 17.

In order to start the operation of the 110 automatic sprayer I employ a cam 24, adjustably secured to the shaft 20 by means of an attaching bolt 24^b which passes through a countersunk arcuate slot 22^c in the dial-plate, and through any one of an arcuate series of bolt holes 24^a in the cam, whereby the cam may 115 be set to any desired circumferential adjustment with relation to the initial stop pin 22^a, or in relation to the adjustable knock-off arm 23^b.

This cam, after a short period of rotation 120 which may be varied by the adjustment above described, engages an anti-friction roller 25 mounted on a tang 25^a, carried in the end of the starting arm 37 of the sprayer mechanism. This tang 25^a is set at an angle of approximately 45° so as to resist the thrust of the actuating cam 24, by which the lever 37 is thrown over to starting position, while allowing the roller to swing out of the path of the cam on the return movement of the cam which 130

is induced by the torsion spring 21 on the shaft 20.

The details of the sprayer mechanism need not be particularly described herein since it forms no part of this invention and is in reality an improvement upon that shown in United States Patent 1,224,095, April 24, 1917 which, in its improved form, forms the subject matter of my co-pending application, now issued as Patent No. 1,585,608, dated May 18, 1926.

For present purposes it will suffice to state that the fulcral end of the arm 37 is secured to a sleeve 32 surrounding the vertical shaft 30 from which both the timer and the sprayer are actuated in proper sequence.

The lower end of this sleeve carries a lateral arm 32^a, which engages an anti-friction roller 32^b on a rocking angle lever 33, which is connected with the stem of the valve 33^a, which is raised to admit water to the oscillating spray-arm 33^b which delivers the spray to the sugar. The oscillatory spray-arm is actuated by a lever 33^c, and combined with it is a cam-roller 33^d arranged to be engaged by a cam 34 in the bottom of the sprayer casing. A tension spring 33^f acts to reversely rotate the rock-arm 33 to close the valve when the rock-arm is released. The lower arm of the angle lever 33 carries a stop pin 33^e which serves, when the lever is in valve-closing position, to support the spray-actuating arm 33^c out of engagement with the cam 34, while allowing said arm to drop until its cam roller 33^d (Fig. 8) rests upon the cam 34 when the lever 33 is rocked to open the valve of the sprayer. As the sprayer construction forms no part of the present invention, since any suitable type of automatically timed sprayer may be used, complete details of its construction need not be recited here as they are fully disclosed in my Patent No. 1,585,608 dated May 18, 1926.

A rotating worm 35, driven by a bevel pinion connection with the vertical shaft 30, is swung into engagement with a timer gear 35^a carrying a knock-off pin 35^b which, after a predetermined arc of rotation, engages a suitably arranged dog or stop-latch 36 to allow the tension spring 33^f whose upper end is connected to a vertical adjusting screw 33ⁱ carried in a lateral extension of the lever 33 and which normally exerts a downward pull on said lever to shut off the liquid and reversely rotate the sleeve 32 to idle position.

It will be understood that any suitable construction of automatically timed spraying mechanism may be used if so related to the centrifugal timing mechanism, previously described, as to be started in operation thereby after the centrifugal has been running for the proper predetermined period of time.

The operation of the device essentially is as follows. By means of the hand-wheel 8, rotated in a clockwise direction from the idle

position shown in Figure 1, the operator throws in the clutch 3 to operatively connect the drive-shaft 1 with the loose pulley 2, and the centrifugal shaft pulley *a* so that the machine is started in operation. By the same movement, through the medium of the lever 11, and the brake-connecting rod 50, the brake-shoes are contracted or released from engagement with the interior of the pulley *a*.

At the same time, by means of the connecting trip-rod 15, the three-arm lever 16 is rotated in a counter-clockwise direction, allowing the weight-arm 13 to drop into stop position to prevent return of the lever 11 to idle position. This same movement of the three-arm lever 16 acts, through the clutch-lever 17, to operatively engage the clutch member 18, splined to the shaft 20 to its convenient driving clutch member 18^a which, in the form shown, is driven from the centrifugal spindle itself by the connecting mechanism, shown in Figure 1 and Figure 6, so that at a single operation the centrifugal is started, the brake is released, the shipper-shaft is locked in operative position and the timer mechanism, which determines the duration of the centrifugal machine operation, is started in motion.

After the timer mechanism has rotated the shaft 20 and the adjustable arm 23, through a predetermined arc, the cam 24, by its engagement with the cam roller 25, throws over the starting lever 37 of the sprayer and starts the spraying operation which continues for a predetermined length of time, according to the setting of the sprayer mechanism. Closely following the completing of the spraying operation the knock-off arm 23 engages the hooked connecting link 40, and by pulling it down rotates the lever 16 in a clockwise direction, raising the weight-arm 13 out of locking position and allowing the shipper-shaft 9 to rotate in a counter-clockwise direction under the action of the torsion spring 6, thereby disconnecting the clutch 3 from the driving pulley 2 and, at the same time, setting the brake-shoes against the interior of the pulley *a* to stop the machine. This same movement of the lever 16 disconnects the clutch 18 of the timer from the timer driving train so that all the mechanism comes to rest and the machine is ready to discharge its load and to receive another, after which the cycle of movements previously described is repeated.

It will be observed that the entire centrifugal mechanism, including the sprayer, requires no attention at all from the operator after he has thrown over the hand-wheel 8 to actuate the shipper-shaft. He is then free to go on to other machines and give them similar treatment, while the complete cycle of operations is automatically continued after a machine is once started by him.

5 The adjustments of the timer mechanism permit any desired variation in the duration of the entire cycle of centrifugal operation or in the period of operation preceding the starting of the sprayer or in the period of operation following the cessation of the spraying operation.

10 The arrangement, therefore, permits the expert foreman of the centrifugal room to accurately fix the duration or period of each operation of the machine and leaves the operation of the machine entirely independent of the judgment of the individual attendant who takes care of it. This is an important 15 feature because the individual workmen are very commonly not expert enough to properly gauge the duration of the various operations, and in consequence of this it often happens that there is excessive waste by washing or insufficient purging of the sugar before the spraying operation. In this way 20 each operation of the centrifugal mechanism is standardized so as to render the apparatus fool-proof against costly mistakes by the 25 operator.

It will be noted in Figure 6 that in order to take up back-lash a short tension spring 17^c, connected with an arm of the lever 17, and with a fixed point of the frame is employed so that there is no danger, through 30 looseness of the connections, that the clutch 18 will be accidentally released during the operation of the machine.

What I claim is:

35 1. In a centrifugal apparatus, the combination with a centrifugal machine and its driving means, of means for starting the centrifugal through its driving connection, a brake and an automatically timed sprayer 40 cooperatively associated with the centrifugal, and coordinated timing means acting to start the operation of the sprayer at a predetermined interval after the centrifugal is started and to apply the brake at a predetermined interval after the spraying operation has 45 ceased.

50 2. The combination with a centrifugal machine and its driving mechanism, of a manually operated starting element movable 55 against yielding resistance to establish operative connection between the centrifugal and its driving mechanism, an automatic timing controller operatively associated with the centrifugal and acting, after a predetermined interval, to release the starting element from operative position, thereby causing the stopping of the centrifugal, and a sprayer interconnected with the controller to be started thereby at a predetermined 60 interval after the starting of the centrifugal and to be stopped after a further interval independently of the further movement of the starting element.

65 3. The combination with a centrifugal sus-

70 associated therewith to operate thereon in alternation to each other, a rotary timer operatively combined with the centrifugal and operating after a predetermined but variable period of rotation from starting position, according to its adjustment, to cause the cessation of the driving action and the setting of the brake, and means operating in coordination with the driving and braking means to restore the timer to said starting position 75 after the timer has completed its operation.

4. The combination with a suspended centrifugal machine and driving and brake mechanism therefor, of a sprayer device for delivering a liquid spray against the purged material walled up in the basket, and means associated with the driving, spraying and braking means provided with variable adjustments for regulating the duration of the successive purging, spraying and drying operations respectively of the machine.

5. In a centrifugal apparatus, the combination with a suspended centrifugal and its starting and stopping means including a self-setting brake, a sprayer, adjustable timing 90 means cooperatively associated with the sprayer and with the brake to control the starting and stopping of the sprayer and also the setting of the brake at predetermined but variable intervals in the operation of the centrifugal.

6. In a centrifugal apparatus, the combination with a centrifugal and its driving and braking means, a shipper for starting the centrifugal and releasing the brake, a rotary timer, a timer-clutch actuated by connections with the shipper, means adjustably secured to the timer shaft to release said timer-clutch and simultaneously produce a reverse drive releasing and brake-setting movement of the shipper to stop the centrifugal and the timer after a predetermined rotation of the timer-shaft.

7. In a centrifugal apparatus, the combination with a rotary centrifugal, a timer-shaft, a sprayer, means for driving said timer and said sprayer from the centrifugal by independently releasable connections, a shipper mechanism for starting and automatically stopping the centrifugal, said sprayer and said shipper being operatively combined with the timer in order to automatically control the duration of the centrifugal operation and of the spraying operation.

8. In a centrifugal apparatus, the combination with a clutch-driven centrifugal, a timer device driven by a releasable clutch connection with the centrifugal, shipper mechanism having separate connections with the centrifugal driving-clutch and with the timer driving-clutch, by which the centrifugal and the timer are started in operation, a brake for the centrifugal also controlled by said shipper, said timer having connections for releasing both clutch mechanisms and set-

ting the centrifugal brake after a predetermined period, the timer device being adjustable to lengthen or shorten the duration of the centrifugal operation.

- 5 9. In a centrifugal apparatus the combination with shipper mechanism for starting and automatically stopping the centrifugal, and adjustable timing mechanism acting to stop the centrifugal after a predetermined period of operation, a self-stopping sprayer device, sprayer starting means adjustably connected with the timer to start the sprayer automatically after any desired predetermined period of operation of the centrifugal.
- 10 15. 10. A centrifugal apparatus for purifying sugar or the like embracing in combination with a centrifugal machine its driving means and a coordinated self-setting brake, normally controlled means for starting the centrifugal and releasing the brake, a sprayer, means whereby the sprayer is started in action at a predetermined but variable interval after starting the centrifugal and is stopped after a predetermined period of spraying, means for discontinuing the action of the driving means and applying the brake at a predetermined interval following the stopping of the sprayer.

In witness whereof, I have subscribed the
30 above specification.

EUGENE ROBERTS.
